US0D1028937S

(12) **United States Design Patent** (10) **Patent No.:** **US D1,028,937 S**
(45) **Date of Patent:** **** May 28, 2024**

(54) **SPEAKER**

(71) Applicant: **New Audio LLC**, New York, NY (US)

(72) Inventors: **Jonathan E. Levine**, New York, NY (US); **Drew Stone Briggs**, Seattle, WA (US); **Thomas C. Wilson**, Brooklyn, NY (US); **David Adjaye**, London (GB)

(73) Assignee: **New Audio LLC**, New York, NY (US)

(**) Term: **15 Years**

(21) Appl. No.: **29/813,970**

(22) Filed: **Nov. 2, 2021**

Related U.S. Application Data

(63) Continuation of application No. 29/765,538, filed on Jan. 8, 2021, now Pat. No. Des. 937,809, which is a continuation of application No. 29/704,067, filed on Aug. 30, 2019, now abandoned, which is a continuation-in-part of application No. 29/599,322, filed on Mar. 31, 2017, now abandoned.

(57) **CLAIM**

The ornamental design for a speaker, as shown and described.

DESCRIPTION

FIG. 1 is a top, front perspective view of a speaker showing our new design.

FIG. 2 is a top, back perspective view thereof.

FIG. 3 is a front elevational view thereof.

FIG. 4 is a back elevational view thereof.

FIG. 5 is a top plan view thereof.

FIG. 6 is a bottom plan view thereof.

FIG. 7 is a side elevational view thereof; and,

FIG. 8 is an opposite side elevational view thereof.

The broken lines in the figures illustrate the portions of the design that form no part of the claimed design.

1 Claim, 4 Drawing Sheets
